UNITED STATES PATENT OFFICE.

S. T. HYDE, OF PIASA, ILLINOIS.

IMPROVEMENT IN HEDGE-TRIMMERS.

Specification forming part of Letters Patent No. 89,769, dated May 4, 1869.

To all whom it may concern:

Be it known that I, S. T. HYDE, of Piasa, in the county of Macoupin and State of Illinois, have invented certain new and useful Improvements in Machines for Trimming Hedges; and I do hereby declare the following to be a full, clear, and exact description of the same, reference being had to the accompanying drawings, in which—

Figure 1 is a plan or top view of a hedge-trimmer embracing my improvements. Fig. 2 is a side elevation of the same, and Fig. 3 is a view of the extensible pitman detached.

Similar letters of reference denote corresponding parts in all the figures.

My invention consists in a novel arrangement of the hinged vertically-adjustable cutting apparatus relative to the fixed vertical cutters; in the construction of the extensible pitman or connecting rod, through which motion is communicated to the adjustable cutters; and in a novel arrangement of means for controlling and turning the machine, as hereinafter explained.

To enable others to understand and use my invention, I will proceed to describe the same with reference to the drawings.

A A' represent a main frame, made in form substantially as represented in Fig. 1, the longitudinal bars or frame-pieces being indicated by A and the transverse bars by A¹. These bars are made of any suitable size to give the required strength to the frame, and are mortised and tenoned or bolted together in the usual manner.

B B' are the main carrying-wheels, one of which, B', is also the driving-wheel, and both of which are mounted on a common axle, C, in such manner as to be free to rotate thereon. The wheel B' is provided with an internally-cogged rim or wheel, D, which gears into and drives a spur-pinion on the inner end of a counter-shaft, E, which is mounted in suitable boxes or bearings on the main frame A, and which is armed at its opposite or outer end with a spur and bevel wheel, F, from which motion is imparted to the two sets of cutters, in a manner hereinafter explained.

G represents a cutting apparatus, which may be constructed with a finger-bar and fingers similar to those usually employed in harvesting-machines, and with the ordinary recipro-

cating scalloped cutter or sickle, or with a series of vibrating shear-blades, such as are represented in the plan view of the hinged cutting apparatus, Fig. 1. This cutting apparatus G is rigidly connected, through the finger-bar g, to the longitudinal frame-piece A, (indicated by a,) by means of a plate or casting, g', firmly bolted to said finger-bar and frame-piece, and is provided at its lower end with an enlarged finger or shoe, made in runner form to facilitate its passage over the ground.

H is a second cutting apparatus, of a construction similar to G, but which, instead of being connected centrally of its length and rigidly to the frame A, is supported at one end in a shoe or plate, H', which is hinged to an adjustable horizontal bar, A², in such manner as to admit of its being depressed or turned down into a horizontal or nearly horizontal position, as represented by the drawing, or raised into a vertical position, forming an extension of the fixed cutter g, or turned into any intermediate position, as desired. The bar A², to which said cutter H' is hinged, is provided at its rear end with a tenon adapted to work or be adjusted up and down in a groove in the upright A³, and may be retained at the desired height by means of a pin or set-screw or other suitable appliance for the purpose.

The forward end of bar A² is adjusted and held at the desired height by means of adjustable bar or bolt A⁴.

The upright A³ may be braced from the main frame in any suitable manner to give it the desired strength and rigidity for the support of the cutter H.

The wheel F, mounted on the counter-shaft E, is beveled on its inner face, or that face adjacent to the drive-wheel, and is provided with teeth, into which the teeth of a bevel-pinion, F', on the rear end of a crank-shaft, f, mesh, as shown in Fig. 1. Said crank-shaft is mounted in boxes or bearings on the transverse frame-bar A¹, (indicated by a¹), and has attached to the crank on its forward end one end of an extensible pitman, c, (see Figs. 1 and 3,) the opposite end of which is connected to a pivoted lever, d, the forward end of which is connected with and drives the cutters of the hinged cutting apparatus in a manner that will be readily understood from the drawing.

The pitman *e* is made in two parts, which are slotted to admit of their relative adjustment, and held together by means of set or thumb screws. By this construction the length of the pitman may be varied to adapt it to the varying distance of the adjustable cutter *H* from the crank-shaft *f*. The wheel *F* is further provided with teeth on its periphery, into which gear the teeth of a pinion, *e*¹, on crank-shaft *e*¹, from which motion is imparted through pitman *e*² and pivoted lever *e*³ to the cutters of the fixed vertical cutting apparatus *G*. The wheel *F* thus serves, through its bevel and spur teeth, to operate both sets of cutters.

I is the pole or tongue, to which the team is attached, and by means of which the machine is propelled or pushed forward over the ground. Said pole is hinged at its forward end to the main frame in such manner as to admit of its being turned horizontally, and is supported at its rear end by means of a caster-wheel, *i*, mounted in a swiveling rod, *i'*, provided at its upper end with a cross-head or levers in such manner as to be under the control of the attendant in his seat or stand on the rear end of pole *I*.

J is a fifth-wheel or semicircular notched plate, hinged to frame *A*, which serves to brace and steady the tongue, and, through latch *j*, working into the notches therein, and the rod or link *j'* and lever *j*² extending to within convenient reach of the attendant, to regulate or hold the tongue against lateral play or adjustment.

k is a sliding rod or link, supported in ways on the tongue and operated by a lever, *k'*. (See Fig. 2.) Said rod *k* is connected at its forward end to one end of a pivoted lever, *l*, the opposite end of which is intended, at the option of the attendant, to bear against the periphery of the outer wheel, *B*, and to act as a brake for the purpose of causing the machine to turn to the right, as hereinafter explained.

K is a lever, hinged to the frame in such manner as to be free to turn horizontally, but made rigid vertically, and extending back to within reach of the driver, for the purpose of enabling him to vibrate the frame *A* on its axle *C*, and thereby to adjust or control the height of the cutting apparatus. In suitable ways on said lever *K* is arranged a sliding rod, *m*, the forward end of which is connected to a right-angled lever, *n*, one arm of which is intended to connect with a sliding clutch, or with the pinion on counter-shaft *E*, for throwing the same into or out of gear with the cogged wheel *D* on driving-wheel *B'*.

The operation of the several parts of the machine in cutting or trimming hedges will be understood without further explanation,

the action of the cutters during the progress of the machine over the ground being similar to that of similar cutters in harvesting-machines, except that the position of the cutters is varied to adapt them to the work for which they are intended.

The greater resistance to the progress of the machine, or what is termed the "side draft," will be on the left or cutter side of the frame, producing a tendency to constantly turn the machine in that direction. This action is resisted by a pin or stop, *o*, in the curved plate *I*, which resists the deflection of the tongue, except when it is desired to turn the machine to the left, when the said stop is removed.

When it is desired to turn the machine to the right the guide-wheel at the rear end of the tongue is turned by the attendant sufficiently to throw the cutting apparatus away from or out of the hedge, when the cutters may be thrown out of gear and the brake applied to the outer wheel, *B*, in the manner explained, thereby changing the side draft to the right, when, by releasing the latch *j* from the notched plate *J*, the machine is turned as desired, after which, the brake being removed from wheel *B*, the machine is again advanced in the required direction over the ground.

It is intended to have a spring connected with latch *j*, so that said latch will be always held in lock with curved plate *I*, except when it is withdrawn for turning the machine.

The opening in the frame at *a*³ between the frame-timbers (indicated by *a* *a*²) allows the cut material to fall to the ground without coming in contact with the frame or tending in any way to obstruct the machine or gearing.

Having now described my improvements, what I claim, and desire to secure by Letters Patent, is—

1. The adjustable hinged cutter *H*, arranged relatively to the fixed vertical cutter, substantially as shown and described.

2. The extensible pitman, constructed as described, in combination with the adjustable hinged cutting apparatus, for the purpose set forth.

3. The employment of the friction-brake *l* and locking lever or latch *j*, arranged as described, for enabling the attendant to control and turn the machine, as set forth.

4. The fixed and adjustable cutters *G* and *H*, in combination with the crank-shafts *f* and *e* and the bevel and spur wheel *F*, all arranged and operating as described.

S. T. HYDE.
